UNITED STATES PATENT OFFICE.

WILLIAM G. JOPSON, OF KEENE, NEW HAMPSHIRE, ASSIGNOR TO JOPSON MANUFACTURING COMPANY, OF BOSTON, MASSACHUSETTS, A CORPORATION OF MASSACHUSETTS.

SHIPPING TAG.

Application filed January 15, 1920. Serial No. 351,528.

To all whom it may concern:

Be it known that I, WILLIAM G. JOPSON, a subject of the King of Great Britain, residing at Keene, in the county of Cheshire and 5 State of New Hampshire, have invented new and useful Improvements in Shipping Tags, of which the following is a specification.

This invention has relation to shipping 10 tags, and has for its object not only to provide an inexpensive tag, but also one which is capable of being strung automatically by machinery.

On the drawings,—

15 Figure 1 illustrates a tag embodying the invention.

Figure 2 shows the under side of the tag.

Figures 3 and 4 illustrate a tag with the staples crossed.

20 Figures 5 and 6 illustrate a tag in which the reinforce consists of a single staple.

Figure 7 represents an edge view of the tag.

The body of the tag, which may be of the 25 usual shape and made of any suitable material, is indicated at 20, having a reinforce

21, which may, if desired, be made of tough stock of some kind used in making the annular reinforces. Through the body of the

30 tag, at one end thereof, there is an aperture *a*, through which emerge the free

ends 22, 23, of the string. In addition, there

are the spaced apertures *b c*, which are located a greater distance from the end of the

35 tag than the aperture or hole *a*, and which are arranged in a line transverse to the length of the tag. The ends of the string are passed through the apertures *b c* so as to form a loop 24, and the ends of the string

40 are then both passed and emerge in the same direction through the aperture *a*, which is nearer the end of the tag than the aperture

b c, so as to leave two converging loops 25, 25, on the under face of the body, which ex-

45 tend from the holes *b c* to the hole *a*. Thus the apertures *a b c* are located at the angles of the triangle, and the loops 24 and 25, 25, constitute, as it were, the three sides of the triangle, the base of which lies against the

50 upper face, and the sides of which lie against the under face of the body. The free attaching ends 22, 23, of the string may be of any desired length. In Figures 1 and

2, I have shown a reinforce consisting of two

55 staples 27, 28, which have their attaching

prongs clinched in the body of the tag and which are arranged adjacent the holes *a b* so as to form bars to resist the pull of the cord and prevent enlargement of the holes. Again, in Figures 3 and 4, the staples 29, 60 30 are shown in crossed relation,—this permitting the holes *a* and *b* to be located closer together and the loop 24 to pass about both staples where they cross, thus giving a double reinforcement at that point. Or, if 65 desired, a single angular staple may be employed as shown in Figures 5 and 6. In this case, the staple has a crossbar 31 and converging end bars 32, 32. The apertures *b c* are located outside the end bars, and the 70 aperture *a* is inside the crossbar, so that the edges of all three apertures are reinforced by metallic bars arranged crosswise of the loops of the cord, and in the angles formed by the cross loop bars and converging loops. 75 The staple is shown as having prongs 34, 34, 35, 35, at the ends of the cross bar, and at the ends of the end bars, which, after being passed through the body of the tag, are clinched.

80 Preferably the reinforces are all applied at the time by the same machine or an attachment thereof, by which the tag is strung, but I do not claim herein the machine for or the method of stringing the tags or applying the reinforces, as these form the subject-matter of an application Serial No. 403,920, filed August 16, 1920.

85 In all three forms in which the invention is illustrated as embodied, I have provided staples which furnish straight metallic bars, which are arranged at an angle to each other, and are located so as to resist the pull of the string against the wall of the apertures *b c* in the tag; and in the third form there is an additional metallic cross bar which lies beyond the aperture *a* to prevent rupture of the tag near said aperture. These cross bars are all so arranged as to resist the pull of the string, when force is applied to 90 the free ends of the string.

95 The staples are all preferably made of flat stock so that, when once clinched in the tag, they will not bend laterally.

100 An advantage of the improved tag is its strength, which is greater than that of any other reinforced tag of which I am aware, the portion of the string which bears on the tag being so supported by a laterally rigid metallic bar that it is not liable to be pulled 105 110

through the margin of the tag by any strain to which it may be subjected.

What I claim is:—

1. A shipping tag having two spaced apertures located at a distance from the end of the tag in a line transverse to the length of the tag and a third intermediate aperture near the end of the tag, a string passed through said spaced apertures and having a cross loop on one face of the tag and converging loops on the other face of the tag, said string having its attaching ends emerging in the same direction through said aperture, and a reinforce consisting of relatively inclined metal bars adjacent said spaced apertures and located in the angles formed by said cross loop and converging loops, said bars being clinched in the tag.
2. A shipping tag having two spaced apertures located at a distance from the end of the tag in a line transverse to the length of the tag and a third intermediate aperture near the end of the tag, a string passed through said spaced apertures and having a cross loop on one face of the tag and converging loops on the other face of the tag, said string having its attaching ends emerging in the same direction through said aperture, and a reinforce consisting of relatively inclined metal bars adjacent said spaced apertures and located in the angles formed by said cross loop and converging loops, said bars being crossed between said spaced apertures and clinched in the tag.
3. A shipping tag having a plurality of string-receiving perforations therethrough, and a pair of relatively inclined straight bars made fast thereto adjacent said perforations and forming reinforcements about which a fastening string passed through said perforations is looped.
4. A shipping tag having a pair of crossed bars made fast thereto, said tag having a plurality of string-receiving perforations located within the angles between said bars, and a fastening string passed through said apertures.
5. A perforated shipping tag having a

pair of crossed reinforcing bars made fast thereto adjacent the perforated portion and about which a fastening string passed through the perforation may bear.

6. A shipping tag having a pair of crossed reinforcing elements, and a fastening string passed through openings in said tag and having a loop bearing over the crossed portions of said elements.

7. A device of the class described comprising a body portion, a pair of crossed reinforcing elements made fast to said body portion, said body portion having a perforation therethrough in the apex of an angle between said reinforcing elements, and an element for attaching said device to an article passed through said perforation.

8. A device of the class described comprising a body portion, a pair of crossed reinforcing elements made fast to said body portion, said body portion having a perforation therethrough in the apex of an angle between said reinforcing elements, and an element for attaching said device to an article passed through said perforation and bearing over said reinforcing elements.

9. A device of the class described comprising a body portion having a perforation therethrough, and a pair of crossed reinforcing bars fixed to said body portion and extending on either side of said perforation.

10. A device of the class described comprising a body portion, and a pair of crossed reinforcing bars made fast thereto, said body portion having a pair of perforations therethrough in the apices of opposite angles between said bars.

11. A device of the class described comprising a body portion having a pair of perforations therethrough, and a pair of relatively inclined reinforcing bars fixed to said portion in position for a fastening element passed through said perforations to bear thereover.

In testimony whereof I have affixed my signature.

WILLIAM G. JOPSON.
